N. D. LEVIN.
MINING AND LOADING MACHINE.
APPLICATION FILED AUG. 7, 1913.

Patented Dec. 31, 1918.

2 SHEETS—SHEET 1.

Fig. 1.

A cross-sectional view of a window frame assembly. The frame is shown in a rectangular outline, with a diagonal cross-hatch pattern on the left side and a solid black pattern on the right side. The assembly includes a top header 36, a bottom sill 37, and a side panel 39. A central vertical post 35 is positioned within the frame. A horizontal track 38 is attached to the bottom of the frame, and a handle 43 is attached to the side panel 39.

UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

MINING AND LOADING MACHINE.

1,290,020.

Specification of Letters Patent. Patented Dec. 31, 1918.

Application filed August 7, 1913. Serial No. 783,564.

To all whom it may concern:

Be it known that I, NILS D. LEVIN, a citizen of the United States, residing at Columbus, in the county of Franklin and State of Ohio, have invented certain new and useful Improvements in Mining and Loading Machines, of which the following is a specification, reference being had therein to the accompanying drawing.

10 The invention relates to mining and loading machines which are provided with means for undermining coal in its natural bed, means for breaking it down out of the said bed, and means for loading it onto cars by means of which it is removed from the mine.

I am well aware that machines for this class of work have been heretofore proposed, but according to earlier proposals, machines constructed to carry on the three operations 20 above enumerated have been adapted only to attack a coal face substantially perpendicularly. According to my invention, the machine can be fed parallelly to the coal face and can undercut and break down a long

25 strip of coal and convey the broken down coal to points relatively remote from the face. The feeding mechanism and the driving mechanism for the undercutting mechanism can be arranged at points at one side 30 of the vertical planes bounding the active part of the undercutting mechanism instead of between the said planes, as in the earlier machines with which I am familiar. This arrangement enables the operative parts

35 to be constructed much more simply and strongly. The principal object of my invention, therefore, is to provide a machine having its parts arranged as above described. Another object of the invention is to provide in a machine of this general character a plate or pan arranged to travel behind the undercutting mechanism in the plane of the bottom thereof to receive the loosened coal and a conveyer arranged to coöperate with 40 the pan to remove material therefrom. Still further objects of the invention are to provide certain improved features of construction which will be fully apparent from the following specification.

45 In order that the scope of my invention may be fully understood I have shown in the accompanying drawings two forms of machine embodying the invention. It will be understood that the constructions shown

are intended merely to be illustrative of the 55 invention and that various modifications and changes can be made within the scope of the claim appended to the specification.

Referring to the drawings—

Figure 1 is a diagrammatic view, in plan, 60 of a mechanism embodying my invention.

Fig. 2 is a diagrammatic view showing, in elevation, the outlines of the vertical cutting mechanism and the breaking down devices.

Fig. 3 is a sectional view of a part of one 65 of the cutter heads.

Fig. 4 is a plan view showing somewhat more in detail the machine shown diagrammatically in Fig. 1.

Fig. 5 is a side view of the machine shown 70 in Fig. 4.

The machine shown in the drawings is provided with an undercutting mechanism which is similar to the mechanisms which have been used for mining machines for long 75 wall work and for mining machines for undercutting transversely across the face of a mine room. It consists of a cutter chain 1 which is driven by a sprocket wheel 2 and which travels in guide ways on a cutter-head 80 3 secured to the main frame casting 4. The sprocket wheel 2 is carried by a vertical head shaft 5 which is journaled in suitable bearings 6 and 7. Near the upper end of the shaft 5 is a master gear 8 which meshes 85 with the pinion 9 on the armature shaft of the motor 10. Conveniently located on the main frame is a bracket 11 in which is journaled a feed shaft 12 carrying a feed drum 13. 14 is a rope adapted to be wound at one 90 end upon the feed drum 13 and to be connected at the other end to a suitable jack 15 which is so located that the stress on the rope will draw the cutterhead into the coal to be cut. Keyed to the upper end of the feed 95 shaft 12 is a worm wheel 16 which is driven by a worm 17 secured to the shaft 18. The shaft 18 is journaled in suitable bearings on the main frame and carries a ratchet wheel 19 which can be engaged by a pawl 20. The 100 pawl is mounted on an arm 21 which is mounted to oscillate about the shaft 18 as a center. By means of the rod 22 the arm 21 is connected to an eccentric 23 on the shaft 5. Journaled on the shaft 18 on opposite sides of the ratchet wheel 19 are arms 24 the outer ends of which are connected together by a trunnioned nut. Threaded in

105

this nut is a screw 26 which is connected to the main frame. Mounted upon the arms 24 is a shield 27 adapted to be carried by the arms into the path of the pawl 20 to hold it 5 out of engagement with the teeth of the ratchet wheel. A hand wheel 28 is secured to the screw 26 and by means of this hand wheel the screw can be adjusted to move the shield with respect to the pawl. As the pawl 10 is oscillated by means of the arms 21 it will be held out of engagement with the ratchet 19 during more or less of its stroke according to the position of the shield 27. In this 15 way the operator by means of the hand wheel 28 can control the rotation of the feed drum 13.

The main frame casting 4 is extended over the floor of the mine to form a flat plate or pan 29. This plate is positioned in the plane 20 of the bottom of the kerf cut by the undercutting mechanism and is adapted to be pushed under any loose coal or slack and to receive any coal that may be loosened and broken down upon it. Formed at the extreme 25 inward and rearward corner of the plate 29 is an upward extending flange 30 to which is secured the frame plate 31 of a vertical cutter head. A cutter chain 33 having cutter bits 34 travels in guide ways at 30 the edge of the frame plate 31 and is driven by the head sprocket 35. Suitable idler sprockets 36, 37 and 38 are provided at the corners of the plate 31. (See Fig. 2). Formed on the surface of the flange casting 35 30 are a plurality of ribs 39 extending horizontally into the kerf formed by the cutter chain and having outward inclined surfaces adapted to exert a wedging action on the coal as the machine is forced forward by 40 the feed mechanism. As the lower of the wedges are positioned in advance of the upper ones the coal will be first broken down at the bottom of the seam in convenient fragments, the removal of which by the conveyer 45 to be described will facilitate the breaking down of the upper part of the coal.

Attached to the bed plate 29 with its forward edge adjacent the breaking down wedges 39, 39 is a gathering conveyer 40 50 of the type in which an endless chain 41, traveling in suitable guides 42, carries horizontally extending flights 43 adapted to gather coal into the trough 44 and convey it therethrough. The chain 41 is driven by a suitable head sprocket secured to a vertical shaft 45 which is driven by means of a bevel gear 46. This bevel gear 46 meshes with a bevel pinion 47 on a longitudinal drive shaft 48 which is supported in bearing 49, 55 50 and 51. The shaft 48 is driven from the main shaft 5 by means of bevel gears 52 and 53. The foot sprocket of the conveyer 40 is journaled on a suitable stub shaft secured to the foot casting 54. This casting 60 65 54 is slideable with respect to the main frame

of the conveyer and can be adjusted by means of the screw 55 to maintain a proper working tension in the chain 41.

The shaft 48 carries at a suitable point a bevel gear 56 which meshes with a bevel gear 70 57 on a transverse shaft 58. This shaft 58 is mounted in bearings 59 and 60 and carries at its inner end the sprocket wheel 35 for the cutter chain 33.

In order to insure the movement of the 75 machine along straight lines I provide a guide rail 61 which engages with suitable guides on the main frame of the machine and serves to prevent angular movement of the 80 machine.

Extending along the working face of the coal and parallel thereto is a conveyer 62 adapted to receive coal from the conveyer 40 and carry it parallelly to the face to conveniently placed cars at or near the end of 85 the face. This conveyer may be of any well known form and its details form no part of this present invention. In the form shown in the drawings for purposes of illustration, the conveyer consists of a sheet iron 90 trough 63 supported at convenient intervals by legs 64 resting directly upon the floor of the mine. An endless drag chain 65 travels along the bottom of the trough to move the coal along it. Suitable bars or 95 rails 66 are secured to the legs 64 below the trough to support the return strand of the chain.

As free floating dust in a coal mine is always objectionable I have provided means 100 for preventing the escape of such dust as may be formed by the cutter bits. Within the frame castings of the cutter heads I have provided passages 67 which are connected by pipes 68 and 69 to a small rotary pump 70 105 which can be driven in any convenient way as for instance from the shaft 48 by means of the belt 71. The pump 70 draws water from a convenient supply such as the reservoir 72 and forces it through the pipes and 110 passages above referred to to jet apertures 73, 73 which are located at the edges of the cutter heads adjacent the chains. These jet apertures are located at the points where the agitation of dust by the bits is greatest and by moistening the dust surface to prevent its 115 flying in the air. A valve 74 is provided in the water supply pipe and by regulating this valve the flow of water can be reduced to a minimum which is necessary for effective 120 laying of the dust.

The claim herein relates to constructions having vertically arranged cutter chains for cutting kerfs on lines inside of the coal face; and I do not herein claim any of the subjects matter of broader scope appearing in my copending application Ser. No. 783,565, filed Aug. 7, 1913.

What I claim is:
In a coal mining and loading apparatus,

the combination of a main frame, a motor thereon, power devices for moving the frame along lines outside of and parallel to the coal face, the cutting mechanism for forming a horizontal kerf at the bottom of the coal, the endless chain cutting mechanism for forming a vertical kerf inside of the front face of the coal, the horizontal plate carried by the frame and extending through the horizontal kerf, the vertically arranged plate secured to the inner edge of the aforesaid plate and arranged to support the said endless vertical kerf-cutting chain and to travel in the vertical kerf, breaking-down wedges carried

by the said vertical plate, power transmitting devices for the vertical kerf-cutting mechanism arranged in the chamber formed by the breaking-down device and behind the latter and the power actuated conveyer having its receiving end on the said horizontal plate and below the breaking down devices and the said power transmitting devices. 15

In testimony whereof I affix my signature in presence of two witnesses.

NILS D. LEVIN.
